PHOTOGRAPHIC AGITATOR

Clarence L. Gay, Detroit, Mich.

Application February 10, 1947, Serial No. 727,694

9 Claims. (Cl. 95—99)

1

This invention relates to apparatus for developing photographic film or plates and for washing photographic prints, and has for its object the provision of a device for mechanically agitating the photographic film or plate within the developing solution and for mechanically agitating the photograph washing bath.

In the developing and printing of photographs, it is necessary to effect relative movement between photograph film and photographs and the developer solution and washing bath over a relatively long period of time which is tedious and time consuming when effected manually. It is, therefore, an object of the invention to provide a simple and economical means by which the operator, after setting the film and photographic sheets in their proper baths, can effect mechanical agitation or relative movement between the baths and the film or prints over any desired timing period without attention.

Another object of the invention is the provision of a photographic agitator providing for the mechanical tilting of washing trays to secure an oscillation of the washing bath over photographic sheets placed in the tray with or without concurrent movement of photograph film or plates in a developer solution.

Another object of the invention is the provision of a photographic agitator in accordance with the preceding object in which the mechanism for tilting the trays and moving the film or plates are counterbalanced to minimize the required power.

Other objects and features of the invention will be readily apparent to those skilled in the art from the specification and appended drawing illustrating certain preferred embodiments in which:

Figure 1 is a perspective view of a photographic agitator according to the present invention.

Figure 2 is an elevational view of the operating mechanism with the other parts shown in broken lines.

Figure 3 is a sectional view on the lines III—III of Figure 2.

Figure 4 is a detail view on the line IV—IV of Figure 2.

Figure 5 is a detail partial view of an alternative developer agitator construction.

The photographic agitator, according to the present invention, comprises a cabinet indicated generally at 1, having a top platform 2 and a bottom platform 3. Inset in the top platform 2 are a pair of washing trays 5 and 6. Between the trays 5 and 6 the platform 2 is provided with an

2

opening 7 leading into a compartment 8 above platform 3. Within the compartment 8 upon intermediate platform 4 are disposed tanks 9 for the reception of a developer solution. Hingedly mounted on the platform 2 are covers 11, 12 and 13 for the trays 5 and 6 and the opening 7.

Upon the platform 3 is mounted a driving motor 14 belted to a pulley 15 driving a crank 16 through a suitable reduction gear 17. To the end 10 of the crank 16 is pivotally connected a link 18, whose upper end is pivoted to a reciprocating block 19. The upper end of block 19 is slotted at 21 to pivotally receive a link 22 pivoted on a fixed bracket 23. At the end of the link 22 is pivotally mounted a reciprocable rod 23 extending through the platform 2 and terminating in a connecting form 25 thereabove. Upon the underside of platform 2 are mounted stationary fulcrums in which are pivotally mounted at 26 and 27 a pair of levers 28 and 29 pivoted at their adjacent ends to a transverse bar 31 mounted on the rod 24. The outside ends of the levers 28 and 29 are pivotally connected to plates 32 and 33 extending through openings 34 and 35 in platform 2 into engagement with the trays 5 and 6 adjacent the ends thereof.

At the upper end of the block 19 is a pin 36 upon which are pivoted a pair of levers 37 and 38 having forked ends 39, 41 pivoted on stationary brackets 42, 42 and 43, 43 and provided with end slots 44 receiving the transversely bent ends 45 of vertically reciprocable rods 46 extending through platforms 2 and 4 at opposite sides of the tank 9. The upper ends of rods 46 are joined in pairs at opposite sides of tank 9 by transverse straps 47, 48 having end portions serving as mounts for the reception of photographic plate holders indicated at 51 and disposed to extend into the developer tank 9.

In the operation of the machine in the arrangement of Figures 1 to 4, operation of the motor 14 will effect rotation of the crank 16 and vertical reciprocation of the block 19. Reciprocation of the block 19 will, through oscillating levers 37, 38 and rods 46, effect vertical reciprocation of the plate holders 51 and of the photographic plates mounted therein within the developer tanks 9. The cover 12 may be closed during this operation, particularly with very fast negatives to exclude light therefrom. Concurrently with the reciprocation of the negatives, the levers 28 and 29 are oscillated about the fulcrum pivots 26 and 27 through their connection with the reciprocating rod 24 and the plates 32 and 33 engage the ends of the washing trays 5 and

6 to effect oscillation thereof and movement of the washing bath over prints placed therein. The washing of the negatives and prints may thus take place concurrently by mechanical operation for any time intervals desired by the operator without the usual tedious manual operations.

One feature of the invention lies in the counterbalancing of the moving parts whereby the trays 5 and 6 are elevated when the holders 5! are lowered and vice versa so that a minimum of torque and power are required from motor 14 to perform the mechanical operation.

In Figure 5 there is shown an alternative construction for the developing of roll film negatives. In this arrangement there is mounted on the platform 2 over the opening 7 a platform 55 in which is disposed a rockable seat 56 to which is connected the connecting form 25 on the rod 24. Upon the seat 56 is adapted to be mounted a receptacle 57 in which roll film is disposed. In this arrangement reciprocation of the rod 24 effects a rocking or oscillating motion of the seat 56 and agitation of the developer solution therein.

While certain preferred embodiments of the invention have been specifically disclosed, it is understood that the invention is not limited thereto, as many variations will be readily apparent to those skilled in the art and the invention is to be given its broadest possible interpretation within the terms of the following claims:

What is claimed is:

1. Photographic apparatus comprising a support, a washing pan on said support, an oscillating lever adapted to engage one end of said washing pan to effect oscillation thereof about its opposite end, a rockable seat, a reciprocable rod connected to said seat, a film and developer receptacle mounted on said seat, means interconnecting said oscillating lever and reciprocable rod, and motor means for concurrently reciprocating said rod and oscillating said lever to oscillate said pan and receptacle.

2. Photographic apparatus comprising a working platform having a plurality of openings therethrough, a washing pan disposed on said platform with an end thereof above one of said openings, means extending through said one of said openings into engagement with said end of said washing pan to effect oscillatory movement thereof, a developer pan supported with at least its main body portion beneath another of said platform openings, reciprocable supports extending above said platform on opposite sides of said developer pan and adapted for the reception of film holders to be disposed for reciprocating movement within said pan, and motor driven means for effecting movement of said supports and of said washing pan oscillating means to effect concurrent relative movement between the baths in said tank and pan and the photographic elements therein.

3. Photographic apparatus comprising a rotatable crank, a reciprocable member driven from said crank, a pair of levers pivotally mounted intermediate their ends and connected at their adjacent ends to said reciprocable member, a pair of reciprocable supports connected to the opposite ends of said levers and projecting upwardly therefrom, a developing tank disposed between said supports and adapted to receive a film holder mounted on said supports for reciprocation within the tank, a second pair of levers pivoted intermediate their ends, means connecting the adjacent ends of said second pair of levers to said reciprocable member, a pair of washing pans, and

means adjacent the remote ends of said second pair of levers engaging each an end of one of said washing pans to effect oscillation thereof to agitate the bath therein.

5. Photographic apparatus comprising a motor driven crank, a reciprocable member driven by said crank, a pair of levers pivoted intermediate their ends and connected at their adjacent ends to said reciprocable member, a pair of reciprocable supports connected to the remote ends of said levers and extending upwardly therefrom, and a developer tank disposed between said reciprocable supports and adapted to receive a film holder mounted on said supports and disposed in the tank for reciprocation therein.

10 6. Photographic apparatus comprising a motor driven crank, a reciprocable member driven by said crank, a pair of levers pivoted intermediate their ends, means connecting the adjacent ends of 20 said levers to said reciprocable member, a pair of washing trays disposed adjacent the remote ends of said levers, and means connected to the remote ends of said levers and engaging said washing trays each adjacent one end thereof to 25 effect oscillation of the trays and movement of the baths therein.

6. Photographic apparatus comprising a motor driven crank, a reciprocable member driven by said crank, a pair of levers pivoted intermediate 30 their ends, means connecting the adjacent ends of said levers to said reciprocable member, a pair of washing trays disposed adjacent the remote ends of said levers, and means connected to the remote ends of said levers and engaging said 35 washing trays each adjacent one end thereof to effect oscillation of the trays and movement of the baths therein, a rocking seat for a developer receptacle and means for connecting said reciprocable member to said rocking seat to effect oscillation thereof and of a developer receptacle mounted thereon.

7. Photographic apparatus comprising a working platform having a plurality of openings therethrough, a washing pan disposed on said platform 45 with an end thereof above one of said openings, means extending through said one of said openings into engagement with said end of said washing pan to effect oscillatory movement thereof, a developer pan supported with at least its main 50 body portion beneath another of said platform openings, reciprocable supports extending above said platform on opposite sides of said developer pan and adapted for the reception of film holders to be disposed for reciprocating movement within 55 said pan, and motor driven means for effecting movement of said supports and of said washing pan oscillating means to effect concurrent relative movement between the baths in said tank and pan and the photographic elements therein, 60 said means effecting movement of said pan and supports in opposite directions so that one is rising as the other is falling whereby their weights tend to counterbalance.

8. Photographic apparatus comprising a support, a developer tank on said support, a reciprocable member, a pair of oppositely directed levers pivoted to said member and pivotally mounted on fixed brackets, said levers having divided ends so that each is of generally Y shape, a plurality 70 of reciprocable rods disposed in pairs at opposite sides of said tank, each of said rods being pivotally connected to a lever end, and negative holder supports mounted on the upper ends of said rods and positioning the negative for reciprocation 75 within the tank.

9. Photographic apparatus comprising a support, a developer tank on said support, a reciprocable member, a pair of oppositely directed levers pivoted to said member and pivotally mounted on fixed brackets, said levers having divided ends so that each is of generally Y shape, a plurality of reciprocable rods disposed in pairs at opposite sides of said tank, each of said rods being pivotally connected to a lever end, negative holder supports mounted on the upper ends of said rods and positioning the negative for reciprocation within the tank, a lever pivotally mounted at one end to said reciprocable member and pivotally mounted intermediate its ends on a fixed bracket, a reciprocable rod pivotally connected to the opposite end of said last mentioned lever, a second pair of oppositely directed levers pivoted at their adjacent ends to said last mentioned reciprocable rod and pivotally mounted intermediate their ends

in fixed brackets, and a pair of washing pans on said support positioned above the remote ends of said second pair of levers to be oscillated thereby.
